UNITED STATES PATENT OFFICE.

AARON A. GOLDSTEIN, OF BUFFALO, NEW YORK.

CUFF BUTTON.

Application filed June 12, 1924. Serial No. 719,561.

To all whom it may concern:

Be it known that I, AARON A. GOLDSTEIN, a citizen of the United States of America, and resident of the city of Buffalo, State 5 of New York, in the United States of America, have invented certain new and useful Improvements in Cuff Buttons, as described in the following specification and illustrated in the accompanying drawings, that 10 form part of the same.

The principal objects of the invention are, to improve the construction of cuff buttons of the type in which two members are temporarily locked together to hold the 15 cuff from accidental separation, providing an extremely strong and rigid construction of fastening for the stud.

The principal feature of the invention consists in the formation of the stud member 20 with a flanged end to be flared within the button portion and to rigidly engage the same.

In the drawings, Figure 1 is a sectional view of a pair of cuff buttons having my 25 improved stud connection.

Figure 2 is a sectional view showing my invention applied to a slightly different form of button.

Figure 3 is an elevational detail of the 30 stud removed from the button.

In the manufacture of cuff buttons of the type wherein two members are temporarily locked together considerable difficulty has been experienced in fastening the holding 35 central stud securely and it is the purpose of this invention to overcome this difficulty by having a stud 1 formed with a shoulder 2 to abut the throat of the ring member 3 forming the inner part of the button.

40 The stem portion 4 of the stud is counterbored and after being inserted into the button 3 an expanding tool is forced into the counterbore to swage the metal of the stud 4 outwardly to form an outwardly flaring 45 flange 5 which interlocks securely with the interior wall of the button. The stud is

thus very rigidly fastened without the necessity of applying solder.

This form of stud may be applied to the form of button illustrated in Figure 50 1 where a releasing stem 6 is passed through the stud and the counterbore forms a natural recess for the spring 7. The same form of stud may be applied to the form of button in which the locking chuck 8 55 is connected to a stem 9 which extends through the crown 10 of the button to pull the chuck clear of the stud.

The securing of the stud in the throat of the button is performed by a very simple 60 and rapid operation.

What I claim as my invention is:—

1. In a cuff button, the combination with a button member having a tapering convergent throat, of a stud having a hollow 65 end swaged outwardly to engage for its entire length the tapering inner wall of the throat in locking contact to secure the stud rigidly therein and against movement relative thereto. 70

2. In a cuff button, the combination with a button member having a tapering convergent throat, of a stud formed with a shoulder to engage the outer portion of the throat, and a hollow tapering extension 75 expanded outwardly within the throat to rigidly interlock the stud for the full length of the hollow extension with the button.

3. In a cuff button, the combination with a button member having a converging body portion and a flaring plate portion formed with a tubular central member extending into the converging body, of a stud having a head thereon, and a shoulder adapted to abut the mouth of said flaring member and having a counterbore extension projecting into the converging body and expanded outwardly within said body together with the inwardly extending portion of the flaring plate to interlock with the body member 80 85 in a permanent non-yielding union. 90

AARON A. GOLDSTEIN.
